(57) **CLAIM**

The ornamental design for a toddler's drinking cup with sleeve and top, substantially as shown.

DESCRIPTION

FIG. 1 is a perspective view of a toddler drinking cup and top showing my new design;

FIG. 2 is a front view of the toddler's drinking cup with sleeve and top, thereof;

FIG. 3 is a rear view of the toddler's drinking cup with sleeve and top, thereof;

FIG. 4 is a right side view of the toddler's drinking cup with sleeve and top, thereof;

FIG. 5 is a left side view of the toddler's drinking cup with sleeve and top, thereof;

FIG. 6 is a top view of the toddler's drinking cup with sleeve and top, according to the first embodiment; and,

FIG. 7 is a bottom view of the toddler's drinking cup with sleeve and top, according to the first embodiment.

The broken line elements in all views are for illustrative and environmental purposes only and form no part of the claimed design.
